UNITED STATES PATENT OFFICE.

STEPHEN KOSTSZEWSKI, OF NEW YORK, N. Y., ASSIGNOR TO ROBERT FINDLAY MANUFACTURING CO., OF NEW YORK, N. Y., A CORPORATION OF NEW YORK.

DESIGN FOR A SPINDLE FOR LIGHTING-FIXTURES.

56,068.

Specification for Design.

Patented Aug. 10, 1920.

Application filed April 15, 1920. Serial No. 374,241. Term of patent 7 years.

To all whom it may concern:

Be it known that I, STEPHEN KOSTSZEWSKI, a citizen of the United States, residing at New York, in the county of New York and State of New York, have invented a new, original, and ornamental Design for a Spindle for Lighting-Fixtures, of which the following is a specification, reference being had to the accompanying drawing, forming part thereof.

The figure is a perspective view of a spindle for lighting fixtures showing my new design.

I claim—

The ornamental design for a spindle for lighting fixtures as shown.

STEPHEN KOSTSZEWSKI.
